(57) **CLAIM**

The ornamental design for a safety helmet, as shown and described.

DESCRIPTION

FIG. 1 is a front view of a safety helmet showing my new design.

FIG. 2 is a rear view of a safety helmet.

FIG. 3 is a left side view of a safety helmet.

FIG. 4 is a right side view of a safety helmet.

FIG. 5 is a top view of a safety helmet.

FIG. 6 is a bottom view of a safety helmet.

FIG. 7 is a front left perspective view thereof with the goggle lowered; and,

FIG. 8 is a front left perspective view thereof with the goggle raised.

The contour shading lines do not represent surface indicia, but are utilized to illustrate the surface contours of the safety helmet in the drawings.

The broken lines in the drawings depict portions of the safety helmet that form no part of the claimed design.
